UNITED STATES PATENT OFFICE.

RALPH G. PACKARD, JR., OF MORRISTOWN, NEW JERSEY.

BOLT GUN.

Application filed June 1, 1922. Serial No. 565,039.

To all whom it may concern:

Be it known that I, RALPH G. PACKARD, Jr., a citizen of the United States, and resident of Morristown, in the county of Morris and State of New Jersey, have invented certain new and useful Improvements in Bolt Guns, of which the following is a specification.

My present invention is shown as being embodied in a breech-loading rifle of the lock-bolt type, but various of the novel features and combinations may be employed to advantage in other types of fire arms.

In the specific form shown the rifle is designed primarily as a high power sporting rifle, but the gun as a whole may well be used as a military rifle for equipment of troops and certain of its novel features would be found highly desirable as additions to or modifications of any of the standard military rifles. The invention and features thereof may also be embodied in other types of guns including target rifles and shotguns.

The general purposes in view and the problems for which my invention affords a solution are much the same as in my prior Patent, 1,202,416, granted October 24, 1916, but the solutions of the problems are novel and in some respects radically different from those in said patent.

Two broad features of similarity are the employment of a thumb trigger with a down-pressure release; also the location of the rear sight on the rear end of the cocking-piece of the firing pin. Even these features, however, are substantially modified to afford novel combinations.

The thumb trigger is guarded almost as well as in the prior patent, but the side guards, instead of having upper sections carried by and sliding with the cocking-piece, are rigid projections carried entirely by the receiver frame. Moreover, they are extended upward so as to afford guards for the rear sight. Thus the rear sight does not have to be non-adjustable and of the massive construction indicated in the patent and may be of slender construction and, if desired, in the form of a bell-crank, the arms of which carry peep sights of two different size apertures, either of which may be swung into operative position, which sight is adjustable for elevation for different ranges and with lateral adjustment for accurately setting or placing the sights. As a result of this construction, the inertia and

friction load on the firing spring is decreased and the response to trigger pull is therefore quicker.

Protection against accidental firing is not limited to the trigger guard, however. The down-pressure thumb trigger is now employed in combination with a down-pressure thumb safety located closely adjacent the thumb trigger. It affords a positive lock on the firing pin, retracting the cocking-detent out of contact with the sear, locking the bolt from being rotated or opened, and, like the thumb trigger, the thumb safety has a down-pressure release.

The lugs that guide the cocking-piece at the rear end of the firing-pin are symmetrically located on the same level with said axis and they slide in the same grooves in which the locking-lugs of the lock-bolt slide when the latter is retracted. These grooves have to open rearwardly in order to permit rearward withdrawal of the lock-bolt, and utilizing the same ends of the grooves as guides for the cocking-piece is a distinct advantage. No other bolt gun has any guide for the cocking-piece and it is absolutely necessary that the cocking-piece be accurately guided where it carries the rear sight.

The cocking-piece, instead of having a single cocking-lug actuated by a single cam on the bolt, has two cocking-lugs symmetrically located on diametrically opposite sides of the firing-pin. Hence when the lock-bolt is rotated to thrust the cocking-piece rearward the pressures are circumferentially balanced and the force applied to compress the firing-pin-spring tends to shove the cocking-piece directly backward without any tendency to cant or jam in the grooves it slides in.

The cocking-piece has two downwardly projecting lugs, the forward one for engaging the trigger-operated sear which holds the piece in a cocked position and the rear one for engaging with the safety cam which is used to lock the firing-pin to prevent accidental discharge when the latter is cocked. The shaft supporting the safety cam is also utilized to operate a forwardly extending bolt adapted to engage a longitudinal slot in the third or rear locking-lug on the lock-bolt, which prevents the bolt being rotated and opened.

An important feature is the means for locking the firing-pin with its spring within

the bolt and to maintain an initial endwise pressure on the firing-spring. The important feature of this is forming the compression sleeve against which the firing-spring abuts, with a lug on one side which can be shoved into a lateral slot with a rearwardly cut recess located in the lower face of the bolt-handle, in which recess the compression lug is retained by the expansive force of the firing-spring. It will be noted that the bolt-handle affords ample space radially of the bolt which can be utilized for the above purpose. By so utilizing it, it becomes possible to keep the rear end of the bolt of no greater diameter than the forward portion thereof and makes it possible for the cocking-piece to slide in and be guided by the same grooves in which the locking lugs of the bolt slide.

The sights employed are novel in several particulars. The rear sight has two apertures, a small one of about $\frac{3}{2}$ inch diameter which is used in ordinary shooting for accurate and long distance work. The other aperture is about $\frac{1}{4}$ inch in diameter and can be rotated into the sight line for use in dim or bad light or in close range snap shooting. The important point is that the latter aperture is used in combination with a large size front bead sight about $\frac{1}{4}$ inch in diameter and which is pivoted so that it can be swung up in front of the fixed front sight to completely conceal the latter from view of the user. This combination makes it possible to have an exceptionally large aperture without making it so difficult to judge when the front sight is centered in said aperture.

Another feature of the coarse sights for use in dim light or in the dark, is providing them with radium paste applied so that it is protected from wear and from the weather. A shallow annular slot is cut in the rear face of the peep sight, the bottom of which is coated with radium or other luminous paint or paste which, in turn, is covered and protected by a sheet of celluloid or similar transparent material. The walls of the groove may be under-cut and the free edges peened or spun inward to retain the celluloid. The forward sight or bead is similarly equipped except that the recess is cylindrical instead of annular.

Another feature is the take-down, the joint of which is as far forward as possible, but not so far as to disturb the fixed relations of the front and rear sights. To this end the receiver frame is made to terminate immediately in the rear of the trigger and the desired strength of the joint is afforded by a massive tension bolt extending through the butt, formed with a T head entering the receiver frame and provided in the butt-plate with a powerful tension screw and a positive lock for the latter. The joint is formed with inner engaging parts such that the stock cannot twist, and the bolt is keyed to

the stock so that the T head will be accurately seated in locking position within the receiver frame.

The above and other features of my invention may be more fully understood from the following description in connection with the accompanying drawings, in which—

Fig. 1 is a side elevation of one form of rifle embodying my invention, an intermediate portion of the barrel only being broken away to save space.

Fig. 2 is a similar view of the receiver frame and parts carried therein, the wooden casing and forehand grip being removed to show its internal construction.

Fig. 3 is a top plan view of the parts shown in Fig. 2.

Fig. 4 is a vertical longitudinal section on the line 4—4, Fig. 3.

Fig. 5 is a horizontal section on the line 5—5, Fig. 4, the locking bolt being removed.

Fig. 6 is a view like Fig. 4 but showing the moving parts in side elevation instead of in section.

Figs. 7 and 8 are enlarged transverse sections on the lines 7—7, 8—8, respectively, Fig. 4.

Fig. 9 is a horizontal section on the line 9—9, Fig. 4.

Fig. 10 is a sectional detail of certain of the parts on the broken line 10—10, Fig. 4.

Fig. 11 is a side elevation of the locking bolt, firing-pin and cocking-piece assembly.

Fig. 12 is a plan view of the parts shown in Fig. 11, viewed from below, the cocking-piece being shown in section on the line 12—12, Fig. 11.

Fig. 13 is an enlarged detail partly in section on the line 13—13, Fig. 12.

Fig. 14 is a detail section on the line 14—14, Fig. 11.

Fig. 15 is a side elevation partly in section showing the butt-stock and the take-down construction.

Fig. 16 is a section on the line 16—16, Fig. 15.

Fig. 17 is a rear elevation of the butt-plate.

Fig. 18 is a perspective view of the nut for the take-down bolt.

Fig. 19 is a full scale elevation of front sight and guards partly in section.

Fig. 20 is a front end elevation of the same.

Fig. 21 is an enlarged rear elevation of the large aperture rear sight.

Fig. 22 is a section on the line 15—15, Fig. 21.

In these drawings the rifle is shown as comprising the stock 1, terminating in butt-plate 2 and take-down fitting 3; the receiver frame 4, closed in below by wooden fore-hand grip and magazine casing 5 and having integral therewith the rear sight guards 6, bridge 7 and breech portion 8 in which is screwed the rifle barrel 9. The

frame forms an open-top slideway for the locking bolt 10 which is rotated and retracted by bolt lever 11 which is provided with the hand piece 12 which may be cut 5 away to Maltese cross section for a purpose to be described.

The forward or breech block end of the frame 4 and of the bolt 10, as also their extractor mechanisms, locking-lugs, etc., 10 may be of the usual Mauser type. The forward breech-locking lugs 13 rotate and lock behind cam shoulders 14 in the breech portion 8 of the frame and, when retracted, they are guided on frame slideways 15 which, 15 in my rifle, extend to and open out through the rear of the frame. (See Fig. 5.) There is a third locking-lug 13^a engaging a similar cam shoulder 14^a in the bottom of the frame opposite bridge 7.

20 The locking-bolt 10 (see particularly Figs. 4, 11 and 12), has the usual cylindrical barrel portion within which the firing-pin 20 is supported and guided in forward bearing surfaces 21, and compression-collar 23, 25 against which the rear end of the firing-spring 24 abuts. The spring propels the firing-pin through integral collar 22. The firing-pin has its rear end detachably connected to the cocking-piece 25, by a sliding fit through aperture 26 through which projects the screw-threaded shank 27 held by nut 28 locked by detent 29. The firing-pin is prevented from rotation by its flattened rear end engaging a flat-sided recess in the 35 cocking piece, as at 27^a, Fig. 4.

The firing-pin is detachably held in the bolt with the firing-spring under compression, by means of the compression-collar 23 which is formed with a radial lug 30, (Figs. 40 11 and 14), having a rearwardly extending detent 31, engaging a rearwardly extending recess 32, formed in the wall of a slot 33 cut in the base of the locking-lever 11, preferably in the under surface thereof. This 45 lug is engaged by forcing the collar forwardly, compressing spring 24, then rotating the collar and then allowing the spring to force detent 31 to locking position. The initial tension of said spring will be sufficient for such purpose. Thus the radial projection necessary for locking of the compression-sleeve is located in the same radial sector that is occupied by the base of the 50 cocking-lever, thereby saving space and is housed within the lock-bolt so as to have free passage rearward when the lock-bolt is retracted for cocking, re-loading or withdrawal from the receiver frame. The front end of the cocking-piece is provided with a pair of 55 symmetrically arranged, forwardly directed, cocking-lugs 32, engaging co-operating pair of rearwardly directed, accurately cut cam surfaces 34 on the rear end of the locking bolt, (see also Fig. 3). The ends of the 60 cocking-lugs are rounded to engage curved

depressions 36 on the rear end of the cocking-bolt into which latter the cocking-piece lugs are spring pressed by the firing spring at the end of the cocking rotation of the bolt, and in which they are non-positively held, while the bolt is being retracted to extract the empty shell in the barrel and feed the loaded shell into the same. The cocking-piece has its side portions formed to slide in a rearwardly extended portion of the 70 grooves 15, 15, which are cut in the frame 4, symmetrically located on the level of the axis of the bolt and the firing-pin, (see Figs. 7 and 10). These are the same grooves 15 through which the bolt-locking lugs 13, 13^a and 13^a, are retracted. The engagement of the cocking-piece therein prevents rotation of the cocking-piece and firing-pin under the rotary effort exerted by the cocking-lugs when the bolt is rotated. The diametrically 80 opposite location of the cocking-lugs 32 prevents the application of any side thrust tending to jam the cocking-piece or firing-pin sidewise. If one of the cocking-lugs or cams 85 happens to be broken, the remaining one 90 will still be capable of operating as effectively as the single lug arrangement in the present-day military rifle.

As will be evident in Fig. 3, the cocking-lugs 32 register with recesses between cams 95 34 whenever the locking-lever 11 is in the locked position, thereby affording space for the longitudinal firing movement of the firing-pin. The cocking-piece and firing-pin are held in the retracted position by means 100 of a downwardly projecting detent 40 engaging the trigger sear 41 on lever 42 pivoted at 43, operated by eccentric or cam projection 44 on lever 45 pivoted at 46 and having a tail piece 47 engaging trigger lever 48 pivoted at 49 and having its long arm 50 snugly engaging the passage 51 through trigger shank 52 sliding in a guide slot 53 and provided at the upper end with an operating thumb piece 54. Said thumb piece 105 54, as also the sear 41, are spring pressed upwardly and all back-lash taken out of the lever system by means of spring 60 in cup 61 in the tail of lever 42. The elevation of the trigger and the corresponding over-lap of the sear 41 with respect to lug 40 may be adjusted by screw 55 which engages the upper side of lever 50.

In the rear of detent 40 is a safety lug 60 formed with a cam surface adapted to engage safety cam 61 carried by sleeve 62 mounted on pivot shaft 63, (see Figs. 3, 6, 8 and 9). Pivot 63 is provided at one end with an eccentric lug 64 which can slide 120 endwise in a recess 65 in the frame 4 and a registering recess 66 formed in the base of safety operating lever 67 which latter projects rearwardly and is formed with a thumb piece 68. The other end of pivot 63 extends through the other side of the frame 125 130

and has screw threaded thereon the nut 69 having the operating head 69^a. The latter head is normally countersunk in the face of the frame but when it is desired to remove the safety, the pivot shaft 63 may be thrust inward, key lug 64 sliding through recess 65 and engaging 66, thereby projecting the head of nut 69 to a position where it may be unscrewed by hand. The unlocked position of the safety is shown in Fig. 4 and the locked position in Fig. 6. In order to provide a spring detent means for nonpositively but firmly holding the locking cams 61, barrel 62, and locking-lever 67 in either the open or closed position, the pivot-pin 63 is recessed as at 70, Fig. 9, to house a helical compression-spring 71, normally thrusting the end face 72 of barrel 62 against the inner face of the frame 4, the abutment of the other end of the spring being against a shoulder 74 within the barrel 62. By this means pivot-pin 63 is yieldingly forced to the left in the position shown in Fig. 9 and with the barrel pressing toward the right against the inner surface of nut 69. Locking-lugs 76 project from said inner face into engagement with diametric V-notches in the end face of barrel 62. There are two sets of these notches corresponding to the "on" and "off" positions of the safety lever. When the lever is shifted from one to the other position, the bolt shifts endwise to the right, Fig. 9, against the pressure of spring 71. The barrel 62 of the safety carries a radial arm 77 engaging a forwardly extending bar-lock 78 which engages a rearwardly opening recess in the rear or third bolt locking lug 13^a, (see Figs. 5, 6 and 11).

The cocking-piece is also provided in the rear thereof with a pivot-pin 80 for the rear sight standard 81 which carries the regular peep sight 82 on an elevating screw 83 which may be rotated with the assistance of thumb wings 84. The pivot screw is such that about four rotations will elevate the sight for a range of say 550 yards which is about the practical limit for ordinary sporting purposes. A fewer number of rotations will change the elevation correspondingly less. As shown in Fig. 7 the thread of the elevating screw is interrupted to form a locking slot as at 85 so that it can be locked for engagement by a suitable locking mechanism (see Fig. 4). This consists of a lever 86 on arm 81^a, pivoted at 87 having one end engaging said locking slot 85 and a forwardly extending arm 86 snugly engaging a plunger 88 sliding in recess 89, normally spring-pressed upwardly by spring 90. On the end of arm 81^a is a peep-sight with a larger aperture 82^a which will be described more fully in connection with the cooperating front sights.

The pivot pin 80 on which the standards

or arms 81, 81^a, are pivoted has an enlarged head 91 (see Figs. 7 and 12) provided with peripheral notches 92 spaced apart 90° and adapted to be engaged by detent 93 pressed forward by spring 94 (see Fig. 12). The shank 80 (Fig. 7) is formed with fine screw threads and the standard 81 is slidably mounted thereon, its transverse position being accurately adjusted by means of nut 95 in order to bring the center line of its aperture and front bead in proper relation to the vertical plane of the axis of the barrel. When set it is locked to the pivot-pin 80 by screw 96, so that the rear sight and its pivot are rigidly associated. The pivot bears and rotates on the periphery of the above-described head 91 at one end and a cylindrical nut 97 at the other end.

By reference to various figures of the drawing, it will be seen that the rear sight 85 is snugly housed between the guards 6, 6, which are cut away at the sides to admit side light on the sight but not sufficiently to impair the protection. Below the sights the guards are substantial imperforate walls 90 and are integral with the receiver frame. They afford protection for the thumb trigger and for the thumb safety.

The co-operative relation of the rear sight and guard with reference to the front sight 85 and guard, as also the construction of the latter, will be evident from Figs. 1, 19 and 20, on Sheet 1 of the drawings. The front sights are mounted on a cylinder comprising a relatively thin body portion 140 with thickened end bands 141, 142, the rear band and part of the cylinder being slotted on the upper side as at 143 to fit lug 144 which latter, as shown in Fig. 19, is preferably integral with the metal of the barrel. The cylinder 140 is held from rearward displacement by lug 144 and also from displacement in either direction by pin 154. The slot 143 is midway between the side guards 145, which are integral with bands 141, 142.

This upper part of the cylinder 140 is thickened to afford lateral bearing as well as lateral protection for the pivot 146 of the large front sight 146, of which the hub 147 is housed between the side guards and in a recess cut in lug 144. Forwardly of slot 143, said thickened portion is formed with a recess-contained detent 148 pressed by spring 149 into engagement with one of the notches 150 on the hub of the pivoted sight. The regular fixed front bead sight is preferably a Lyman sight having the usual bead 152, the blade being cut off at the ends as shown and inserted in a vertical slit where it is held by transverse pin 153.

As shown more clearly in Fig. 20, the height of the pivoted bead is such that when in use in the raised position it hides from view the fixed sight 152. In either position it is housed within the guards and in the

lowered position projects just enough beyond the lug 144 to afford a thumb hold for raising it to the operative position shown in dotted lines.

As before explained this pivoted front bead, as also the co-operating rear peep sight 82^a, are of very large size, preferably about $\frac{1}{4}$ inch for the bead and $\frac{1}{4}$ inch for the peep aperture, particularly adapting these

10 sights for snap shooting and dim lights.

For very dim light, these sights are illuminated by radium or other phosphorous paint preferably permanently applied in the manner indicated in Figs. 21 and 22. For this 15 purpose the rear face of the rear sight is formed with a groove 160 in the bottom of which is a layer of luminous paint or paste 161, covered by a layer of celluloid 162 which latter may be sprung into place or 20 secured by peening the metal around the edges of the groove. The co-operating front sight 146 has its face similarly equipped except that the recess, paint and celluloid are 25 in the form of a solid disc or circle instead of an annulus.

The take-down joint is as far forward as possible without disturbing the relations of the front and rear sights. The rear end of the frame terminates practically in the plane 30 of the rear and of the trigger and sight guards, the rearwardly directed surface of the frame being formed with a recess 101 into which fits a projection 102 on butt-plate 3 secured to the butt-stock 1 by screw 103. 35 The engaging surfaces are formed so as to afford a wide accurate bearing surface, and rotary displacement of the stock is prevented by having the projection 102 and recess 101 noncircular. The frame 4 is provided with 40 a central vertically elongated hole 104 through which passes the T head 105 of tension bolt 106. The sides of the hole are formed with interior ribs 107 with accurately formed seats 108 in which the T head 45 may rest when the bolt is rotated around from the vertical position for entrance to the horizontal locking position indicated in Figs. 2, 8 and 16. The bolt adjacent the T head has a cylindrical enlargement fitting 50 the width of hole 104 in the rear end of the frame and accurately fitting the cylindrical hole 110 in plate 3. There is a short key 111 engaging a key slot in 102 to prevent rotation of the bolt with respect to the stock, 55 after assembly but the bolt can slide forward to permit rotation of the bolt with respect to the frame when the parts are being taken down or put together.

Bolt 106 extends freely through a passage 60 112 in the stock, the passage being so much larger than the bolt that considerable spring or angular movement of the stock will not bring the bolt in position to apply transverse strains to the stock. That is to say, the stock

1 is really a distance block acting almost 65 solely as a compression-member under the powerful tension applied through the bolt 106.

The screw-threaded rear end of bolt 106 passes freely through an opening 113 in a 70 pocket 114 formed in the butt-plate 2. The bottom of the pocket 114 is arranged at right angles to the axis of the bolt so as to afford a true surface bearing for lock nut 115. This nut is shown as provided on the outer 75 end with concave recesses of Maltese cross form adapted to be engaged by the above-described handle piece 12 of the locking-bolt lever 11, which is used as a spanner to set up the nut 115 applying a maximum tension 80 for bolt 106 with corresponding compression of stock 1 against the rear surface of the receiver frame. The periphery of the nut 115 is formed with closely spaced peripheral recess 116 adapted to be engaged by detent 85 117 urged by spring 118 held in place by screw 119. The detent is provided with an operating member 120 by which it may be retracted and there is in the butt-plate a recess 121 into which 120 may be turned to 90 hold the detent in the withdrawn position.

The butt-plate has a trap-door 125, closing recess 126 spring retained in either the open or closed position by means of spring 127 secured by screw 128 and having its free end 95 adapted to bear either on surface 129 or 130, according as the trap is open or closed. The butt-plate has preferably integral therewith an ear 131 on which is secured by pivot 132 the sling-strap hanger 133. The magazine 100 for automatically feeding the cartridges in front of the bolt 10, when the latter is retracted, comprises the follower 170, spring 171, and pivoted closure 172, may be of any known or desired construction. The closure 105 may be secured in the closed position by bolt 173 adapted to be retracted against the pressure of spring 174 by a bullet or other implement applied in recess 175.

The spring-pressed ejector finger 180 and 110 rear detent 181 for the firing bolt 10 and the operating parts therefor within pivoted casing 182 may also be of any known or desired construction.

The reloading operation, including cocking, is accomplished merely by rotating the bolt handle 11 upwardly as far as it will go, pulling it rearward as far as it will go, pushing it forward as far as it will go, and rotating it back to the initial position.

The upward rotation frees the locking-lugs 13, 13^a, from the locking-shoulders 14, 14^a, and cams the breech rearward a slight distance by engagement with cam surface 7^a on bridge-piece 7. This gives powerful 125 retraction on the extractor for freeing expanded or ill-fitting shells. Also it rotates the cocking-lugs which retract the cocking-

piece and with it the firing-pin, preferably about two-thirds the distance required for cocking.

Then the straight rearward pull completes extraction of the shell, permits operation of the ejector and also permits the magazine follower force a new cartridge upward in front of the breech end of the bolt. The rear pull also carries the cocking-lug 40 a considerable distance behind the trigger sear 41.

In the subsequent forward movement this lug engages the sear and, on the rotary closing movement, the lever 11 is cammed forward by cam surface 7^b against the pressure of the main spring, thus completing the cocking compression of the latter, at the same time screwing home the breech.

These operations are performed when the safety is off so that the firing-pin block and the locking-lug lock are both in the inoperative position. When the gun has been closed, putting the safety on by lifting the safety lever, forces the locking-bar forward into engagement with the recess in the third locking-lug, thereby locking the bolt and lever against opening. Such lock is desirable because, as will be noted, the firing-spring is then under considerable pressure which might facilitate accidental rotation and opening of the bolt.

It will be noted that in the foregoing the part 10, which in some respects resembles a tube more than it does a bolt, is called a locking-bolt because that is the technical name for it; also that it has several functions and may be called, with equal propriety, breech-bolt, cocking-bolt, reloading-bolt, lock-bolt or just plain "bolt" according to the connection in which it is being described.

It will also be noted that the part 20 is called a firing-pin, for a similar reason; also that it has several functions including support guide and compression of the firing-spring; also the rear end of it is formed or provided with means for its own cam retraction through the cocking-lugs and also the groove and spline engagement with the frame which prevents it from rotating when the rotary stress is applied on the cocking-lugs. Hence functionally considered it is immaterial whether the firing-pin and the so-called cocking-piece are integral or, for structural reasons, are in the form of the two separate but rigidly associated members which are called the firing-pin and the cocking-piece. The two combined constitute a plunger provided with firing, splining, cocking and spring carrying and compressing elements; also affording an angularly stable support for the rear sight.

I claim:

1. A gun having a firing-plunger slidably mounted in approximate alinement with the axis of the barrel; a firing-spring

engaging said plunger; means for holding the plunger in the rearward cocked position with the spring under compression; a peep sight mounted on the rear end of the plunger; and spline elements also carried by the rear end of the plunger and closely fitting straight side grooves carried by the frame; the spline projections and the grooves therefor being diametrically opposite each other on the same level with the axis of the firing-plunger.

2. A gun having a firing-plunger, slidably mounted in approximate alinement with the axis of the barrel; a firing-spring engaging said plunger; means for holding the plunger in the rearward cocked position with the spring under compression; a peep sight mounted on the rear end of the plunger; rigid stationary guards on the frame extending above said peep sight; and splined means also carried by the rear end of the plunger and snugly fitting side grooves carried by said guards.

3. A gun having a firing-plunger slidably mounted in approximate alinement with the axis of the barrel; a firing-spring engaging said plunger; means for holding the plunger in the rearward cocked position with the spring under compression; a peep sight mounted on the rear end of the plunger; rigid stationary guards on the frame extending above said peep sight; and splined means also carried by the rear end of the plunger and snugly fitting side grooves carried by said guards; and means for mounting said sight including a transverse screw on which said sights may be laterally adjusted; means for locking the sights to the screw in the adjusted position.

4. A gun having a firing-plunger slidably mounted in approximate alinement with the axis of the barrel; a firing-spring engaging said plunger; means for holding the plunger in the rearward cocked position with the spring under compression; a peep sight mounted on the rear end of the plunger; spline elements also carried by the rear end of the plunger and closely fitting side grooves carried by the frame; the spline projections being diametrically opposite each other parallel with the axis of the firing-plunger; together with a second rear sight rigid with said first-mentioned sight and at right angles thereto; and means for mounting said sight including a transverse screw on which said sights may be laterally adjusted; means for locking the sights to the screw in the adjusted position and bearings carried by the cocking-piece in which the ends of said screw are rotatably mounted.

5. A bolt gun including frame, bolt, firing-plunger and spring; a cocking-piece on the rear end of the plunger; a peep sight mounted on the cocking-piece; stationary guards on the frame extending up above the

top of the peep sight; and spline projections on the cocking-piece closely fitting grooves in the guards.

6. A bolt gun including frame, bolt, firing-plunger and spring; a cocking-piece on the rear end of the plunger; a peep sight mounted on the cocking-piece; stationary lateral guards on the frame extending up above the top of the peep sight; and spline 10 projections on the cocking-piece closely fitting grooves in the guards; and laterally covering its cocked and uncocked positions.

7. A bolt gun including frame, bolt, firing-plunger and spring; a cocking-piece on 15 the rear end of the plunger; a peep sight mounted on the cocking-piece; stationary guards on the frame extending up above the top of the peep sight; and spline projections on the cocking-piece closely fitting grooves 20 in the guards; and laterally covering its cocked and uncocked positions, said grooves in the guards and said spline projections on the cocking-piece being located at the level of the axis of the plunger.

8. A gun having a firing-plunger, slidably mounted in approximate alinement with the axis of the barrel; a firing-spring engaging said plunger; means for holding the plunger in the rearward cocked position with the spring under compression; a peep sight mounted on the rear end of the plunger; rigid stationary lateral guards on the frame extending above said peep sight; and splined means also carried by the rear 35 end of the plunger and snugly fitting side grooves carried by said guards, and a take-down joint between the forward end of the stock and the rear end of the frame; and means for detachably locking the stock and 40 frame in assembled position.

9. A bolt gun including stock, frame, barrel, locking-bolt, firing-plunger slidably mounted in the bolt, a peep sight mounted on the rear end of the firing-plunger, stationary guards on the frame extending above the top of the peep sight, spline projections on the cocking-piece closely fitting lateral grooves in the guards, and a take-down joint between forward end of the stock and the rear face of the frame; and means for detachably locking the stock.

10. A bolt gun having a peep sight mounted on the rear end of the cocking-piece and stationary lateral guards extending to the level of said sight and wherein the bolt operating lever is formed with a recurve to clear the top of the guard while the hand grasp portion of the lever projects horizontally.

11. A bolt gun including a locking-bolt having locking-lugs and a laterally extending lever by which it may be rotated and reciprocated; a frame having grooves in which said locking-lugs slide and a recess into 60 which the base of said lever rotates for lock-

ing; a firing-plunger reciprocating in said locking-bolt and having its rear end splined by lugs sliding in said grooves of the frame in which said locking-lugs slide; a sight mounted on the rear end of said plunger; 70 stationary guards on the frame projecting above the level of said sight; said lever being formed with a radial portion recurved so as to clear the top of the guard when the locking-bolt is reciprocated and so that the 75 free end of the lever lies close to the frame when in the locked position.

12. A bolt gun including a locking-bolt having locking-lugs and a laterally extending lever by which it may be rotated and reciprocated; a frame having grooves in 80 which said locking-lugs slide; a recess into which the base of said lever rotates for locking; a firing-plunger reciprocating in said locking-bolt; a sight mounted on the rear 85 end of said plunger; stationary guards on the frame projecting above the level of said sight; said lever being formed with a radial portion recurved so as to clear the top of the guard when the locking bolt is reciprocated and so that the free end of the lever 90 lies close to the frame when in the locked position.

13. A bolt gun having a breech bolt with locking lugs carrying a firing pin provided 95 with a cocking piece having lateral lugs to prevent rotation thereof; and a frame provided with stationary guards projecting above the level of the cocking-piece and extending rearwardly of the cocked position 100 of the latter and formed with lateral grooves in which the lugs of the cocking-piece slide, said grooves constituting rearward extensions of the grooves in which the bolt locking-lugs slide.

14. A bolt gun having a breech bolt with locking lugs carrying a firing pin provided with a cocking piece having lateral lugs to prevent rotation thereof; and a frame having 110 on the upper side thereof a thumb trigger and a thumb safety located beneath the cocking-piece when in the cocked position and stationary guards extending above the level of the cocking-piece, the latter having sliding engagement with said guards on the level of the axis of the firing bolt.

15. A bolt gun including a receiver frame, cocking-bolt with locking-lugs having rotary and sliding engagement with said frame; a firing-pin slidably mounted in the bolt; a cocking piece secured to the rear end of the firing pin and having lugs engaging longitudinal grooves in the frame; and a peep sight mounted on the cocking piece; stationary side guards on the frame covering the rear end of the firing bolt and the peep sight when in the cocked position and extending above the level thereof.

16. A bolt gun including a receiver frame, 130 a cocking-bolt having locking-lugs, a firing-

pin carried by the bolt and a cocking piece including cocking lugs, said receiver being formed with longitudinal grooves parallel with the axis of the barrel and having circumferential extensions in which said locking-lugs of the bolt can be rotated for opening the breech and retracting the cocking-piece including cocking lugs; said cocking-piece fitting and sliding in the rear portion 10 of the same longitudinal grooves of the receiver in which said locking-lugs slide.

17. A bolt gun including a receiver frame, an operating bolt having locking-lugs, a firing-pin carried by the bolt and a cocking-piece carried by the firing-pin including cocking lugs, said receiver being formed with longitudinal grooves open at the rear end and in which both said cocking-piece lugs and said locking lugs slide.

18. A bolt gun including a frame, cocking-bolt, and firing-pin, in combination with a safety comprising an eccentric block element pivoted on a transverse axis beneath the firing-pin and a rearwardly projecting operating lever, releasable by pressure of the thumb of the user when the hand is in the firing position, the pivotal mounting including a shaft keyed to the gun, a sleeve on the shaft and axially inter-engaging detent elements on shaft and sleeve for non-positively holding the safety in either the locked or released positions.

19. A bolt gun including a frame, cocking-bolt, and firing-pin, in combination with a thumb trigger and a thumb safety on the top of the gun, said safety including inter-dependent operating means for blocking the firing-pin in the rearward position and for locking the cocking-bolt in the closed position.

20. A gun including a receiver frame, a firing-plunger and firing-spring operating substantially in alignment with the barrel, in combination with a rear sight on the rear 45 end of the firing-bolt and fixed guards extending upwardly from the frame substantially above the level of said sight and located so as to laterally cover the sight both in the cocked and uncocked positions of the firing-pin which carries it, in combination with a thumb trigger located between said guards below the level of said firing-bolt.

21. A gun including a receiver frame, firing-plunger, a cocking piece having laterally projecting slide lugs for the latter, and a peep sight on the cocking piece in combination with guards extending above the level of the peep sight and provided with longitudinal grooves in which said lugs slide 60 between cocked and uncocked positions, and a thumb trigger located between said guards below said plunger.

22. A bolt gun including a receiver frame having longitudinal grooves, a locking bolt having locking-lugs adapted to slide in said

grooves, a firing-pin slidably mounted in said cocking-bolt, a cocking-piece carried by said firing-bolt, said cocking-piece having lateral lugs fitted and slidable in the same grooves in which the locking-lugs slide, said frame including stationary guards extending 70 above the level of the firing-bolt.

23. A bolt gun including a receiver frame having longitudinal grooves, a locking-bolt having locking-lugs adapted to slide in said 75 grooves, a firing-pin slidably mounted in said cocking-bolt, a cocking-piece carried by said firing-bolt, said cocking-piece carrying a peep sight and having lateral lugs fitted and slidable in the same grooves in which the locking-lugs slide, said frame including stationary guards extending above the level of the peep sight and a safety block for the firing-bolt pivoted between said guards and having an operating lever extending rear- 80 wardly.

24. A bolt gun including a receiver frame having longitudinal grooves, a locking-bolt having locking-lugs adapted to slide in said 90 grooves, a firing-pin slidably mounted in said cocking-bolt, a cocking-piece carried by said firing-bolt, said cocking-piece having lateral lugs fitted and slidable in the same grooves in which the locking-lugs slide, said frame including stationary guards extending 95 above the level of the firing-bolt; and a safety-block for the firing-bolt pivoted between said guards and having an operating lever extending rearwardly; and a thumb-trigger also between said guards. 100

25. A bolt gun including a receiver frame having longitudinal grooves, a locking-bolt having locking-lugs adapted to slide in said grooves, a firing-pin slidably mounted in said cocking-bolt, a cocking-piece carried by 105 said firing-bolt, said cocking-piece having lateral lugs fitted and slidable in the same grooves in which the locking-lugs slide, said frame including stationary guards extending above the level of the firing-bolt; and a safety-block for the firing-bolt pivoted between said guards and having an operating lever extending rearwardly; and a thumb-trigger also between said guards, on the right-hand side of the safety-operating 110 lever. 115

26. A bolt gun including a frame, cocking-bolt, firing-pin and cocking-piece, in combination with trigger and safety mechanisms including separate trigger and safety 120 release elements close together and releasable by movements in the same direction by the same thumb while the hand is in the firing position.

27. A bolt gun including a frame, cocking-bolt, firing-pin and cocking-piece, in combination with trigger and safety mechanisms including separate trigger and safety 125 release elements close together and releasable by movements in the same direction by 130

the same thumb while the hand is in the firing position, the movement for safety release being much longer than the trigger release movement.

5 28. A bolt gun including a frame, cocking-bolt, firing-pin and cocking-piece, in combination with trigger and safety mechanisms including separate trigger and safety

10 release elements close together and releasable by movements in the same direction, the trigger release movement being very short and approximately rectilinear and the safety release movement being circular and relatively long.

15 29. A bolt gun including a frame, cocking-bolt, firing-pin and cocking-piece, in combination with trigger and safety mechanisms including a thumb trigger and a thumb safety on the top of the gun, both

20 within reach of the thumb of the user when the stock is gripped with the hand in the firing position, stationary lateral guards on the gun protecting said parts throughout the cocked and uncocked positions.

25 30. A bolt gun including a frame, locking-bolt, and firing-plunger, said bolt being provided with a plurality of symmetrically arranged front locking-lugs and a rear locking-lug, in combination with a thumb operated safety blocking mechanism for the firing-plunger, which safety also locks said rear locking-lug against rotation.

30 31. A bolt gun including a frame, locking-bolt, and firing-plunger, said bolt being provided with a plurality of symmetrically arranged front locking-lugs and a rear locking-lug, in combination with a thumb operated safety-lock mechanism for the plunger, which safety also locks a detent for positively locking the rear lug of the bolt against rotation when in the bolt-locked position.

35 32. A bolt gun including a frame, locking-bolt, and firing-plunger, said bolt being provided with a plurality of symmetrically

arranged front locking-lugs and a rear locking-lug, in combination with a thumb operated safety mechanism for the plunger and for the locking-bolt including a detent and means for moving it to the lug-locking position when the safety is on and to the unlocked position when the safety is off. 50

33. A bolt gun including a frame and, slidably mounted therein, a bolt having locking lugs and having laterally projecting handle for rotating and reciprocating it; a firing-spring encircling the plunger and means for compressing and sustaining the thrust of the spring including a forward compression member fixed to the plunger and a rearward collar within the bolt and encircling the plunger and means for locking said collar to the bolt including a radially projecting detent housed in a recess in the base of the bolt handle. 55

34. A bolt gun including a frame and, slidably mounted therein, a bolt having an open rear end and provided with a laterally projecting handle for rotating and reciprocating it; a firing-plunger having its forward end slidably mounted in the forward end of the bolt and carrying a forward compression member; a firing-spring encircling the plunger and having its forward end in engagement with said compression member, 70 said plunger, spring and compression member being insertable through the rear of the bolt; and means affording a rear guide for the plunger and sustaining the thrust of the spring including a rear collar encircling the plunger and fitting in the rear end of the bolt; and means for locking said collar to make it rotate and reciprocate with the bolt, 75 said means including a detent at the base of the bolt handle and rotating with it. 80

Signed at New York, in the county of New York, and State of New York, this 31st day of May, A. D. 1922.

RALPH G. PACKARD, JR.
